(57) **CLAIM**

The ornamental design for a carry bag as shown and described.

DESCRIPTION

FIG. 1 is a perspective view of a carry bag showing the new design.

FIG. 2 is a side view of thereof.

FIG. 3 is a side view of thereof.

FIG. 4 is a side view of thereof.

FIG. 5 is a side view of thereof.

FIG. 6 is a top view of thereof; and,

FIG. 7 is a bottom view of thereof.

The broken lines on the surface of the bag depict stitching that forms part of the claimed design. The broken lines illustrating a zipper and zipper pull form no part of the claimed design.

1 Claim, 5 Drawing Sheets
